CURTAIN STRETCHER

James J. Dvorak, Chicago, Ill.

Application September 21, 1945, Serial No. 617,721

10 Claims. (Cl. 45—24)

1

Heretofore household curtain stretchers have been of various complicated types consisting of a great many separate members and a large number of detached fastening means, which are easily lost or misplaced, so that the ordinary run of curtain stretchers has been a bane or nightmare to housewives attempting to assemble the curtain stretchers and adjust the same to required sizes with only the use of scale markings on the frame members. A further inconvenience and objection to the use of the old type of curtain stretchers is the fact that the end frame members overlap the horizontal frame members in such a manner that the curtain stretching pins on said end and horizontal members are disposed in different planes requiring the ends of the curtains to be supported on pins which are on a level different from the level of the pins on which the longitudinal edges of the curtains are engaged.

The present invention pertains to a collapsible type of curtain stretcher, primarily adapted for use by housewives or in small establishments. The curtain stretcher is simple and inexpensive and furthermore is designed and constructed with improvements for increasing the adaptability and efficiency thereof.

It is an object of this invention to provide a collapsible type of curtain stretcher of a minimum number of units adapted to be readily assembled and sized.

It is also an object of this invention to provide a collapsible type of curtain stretcher consisting of only three group units adapted to be readily assembled and sized by means of a series of separately identified fastener receiving openings to insure convenient and positive sizing of curtains.

Still another object of the invention is the provision of a simplified and easily assembled type of collapsible curtain stretcher wherein the stretcher pin frame members are adapted to be assembled to position all of the stretcher pins in the same plane.

It is furthermore an object of the invention to provide a collapsible type of curtain stretcher including an end frame member which carries spring controlled frictionally contacting pin-carrying blocks adapted to be swung collectively or individually into and out of stretching position to position the stretcher pins for said end member in the plane of the pin members of the remaining frame members of the curtain stretcher.

Still another object of the invention is to provide a collapsible type of curtain stretcher consisting of only three easel units one of which is adapted to be set up to be self-supporting to facilitate the attachment of the remaining two easel units thereto.

It is an important object of this invention to provide an adjustable type of curtain stretcher wherein the stretcher pins of the frame mem-

bers are all adapted to be positioned in the same plane, and wherein there is always a pin in each corner of the frame for all sizes to which the curtain stretching frame may be adjusted.

Still another important object of the invention is the provision of a collapsible type of curtain stretcher including a middle or intermediate easel unit adapted to be self-supporting and to which the upper and lower frame members are permanently but adjustably affixed.

An important feature of the invention is the construction of a flat type of curtain stretcher including an end frame unit wherein a row of stretcher pin carrying blocks are spring pressed into frictional engagement with one another, on a common control which is operable for moving the blocks collectively into position to position the block pins in the same plane as the stretcher pins of the remaining members of the curtain stretcher frame.

Still another object of the invention is the provision of an improved and simplified form of collapsible curtain stretcher consisting of three frame forming units, the assembly means for which are permanently attached thereto and are adjustable for assembling the frame units into desired different sizes to facilitate the stretching of curtains of different sizes.

An important feature of the invention is the construction of an adjustable and collapsible type of curtain stretcher wherein the stretcher pins of the frame members are all adapted to be disposed in the same plane including corner pins, and wherein the frame is adapted to be adjusted to predetermined sizes by positive and properly identified means registering with receiving holes or recesses whereby the proper holes for the correct sizing of the stretcher frame may be quickly and positively selected.

Another important feature of the invention is the provision of a collapsible type of curtain stretcher consisting of only three easel supported units, provided with rows of properly identified size determining recesses for selectively receiving frame bolting or securing means which are permanently identified with the curtain stretcher forming units.

Still another object of the invention is to provide a curtain stretcher wherein a self-supporting intermediate unit permanently and adjustably carries the upper and lower frame members to facilitate the quick and easy setting up of the curtain stretcher frame by attaching end units in such a manner that the stretcher pins are all disposed in the same plane and wherein corner pins are always provided in all size setups of the curtain stretcher.

Another important object of the invention is to provide a quick set up type of collapsible curtain stretcher, wherein the stretching of curtains

of different sizes is adapted to be accomplished by the adjustment of a lower horizontal frame unit with respect to an upper horizontal frame unit, and by the adjustment of an end unit which carries a row of pin carrying keys provided with identified sizing means for attachment to the horizontal frame units when the pin carrying keys are retracted, said keys adapted to be simultaneously moved into curtain stretching position with the exception of certain pin carrying keys which are restrained from being moved by the positioning of the lower horizontal frame member.

For the attainment of the foregoing and other objects and advantages, the invention preferably consists in the details of construction and the arrangement and combination of the parts to be hereinafter more fully described and claimed, and illustrated in the accompanying drawings.

On the drawings:

Figure 1 is a front elevational view of the improved curtain stretcher, partly broken away, but set up for use and illustrating the positioning of two of the frame members in dotted lines with respect to the remaining two frame members to illustrate the assembly of the stretcher frame for the stretching of curtains of different sizes;

Figure 2 is a front elevational view of the middle or intermediate self-supporting curtain stretcher unit, with the upper and lower horizontal frame members illustrated in collapsed position on the intermediate supporting standard, and furthermore illustrating in dotted lines the positioning of the upper and lower horizontal frame members in extended position to permit the end frame units to be attached thereto;

Figure 3 is a side elevational view of the main or intermediate curtain stretcher unit, in the collapsed form illustrated in Figure 2, and having the rear easel leg extended into bracing position to support the unit;

Figure 4 is a fragmentary front elevational view of the right-hand side of the curtain stretcher with the end frame member moved inwardly from the ends of the horizontal frame members, and illustrating the out-of-the-way position of the pin carrying keys in dotted lines and also showing the keys moved into full line curtain stretching position after the end members are bolted into place, with the lower horizontal frame member acting as a stop to cause two of the pin carrying keys to be retained in open or retracted position to permit the fastening means to be engaged in predetermined holes in the right-hand end member and in the lower horizontal frame member to permit stretching of a curtain to a predetermined size;

Figure 5 is a vertical sectional view taken on line V—V of Figure 4 showing the easel brace leg of the right-hand frame member in open position;

Figure 6 is an enlarged fragmentary sectional detailed view taken on line VI—VI of Figure 4 illustrating the spring compressed frictional relationship of the row of pin carrying blocks or keys shown associated with the common control rod for simultaneously moving the pin carrying keys into either open or closed position;

Figure 7 is an enlarged fragmentary detail sectional view taken on line VII—VII of Figure 1 showing the connecting means at the upper left-hand corner of the curtain frame;

Figure 8 is an enlarged detail sectional view taken on line VIII—VIII of Figure 1;

Figure 9 is an enlarged transverse detail sectional view taken on line IX—IX of Figure 4 with all of the pin carrying keys in retracted or open

position such as shown in dotted lines in Figure 4 to facilitate adjustment of the right end frame member and the lower horizontal frame member when the stretcher frame is being sized;

Figure 10 is a similar enlarged transverse detail section taken on line X—X of Figure 4 with substantially all of the keys moved into curtain stretching position with the exception of two keys which are prevented from being moved by the adjusted position of the lower horizontal frame member;

Figure 11 is an enlarged fragmentary top plan view of the upper corner of a modified form of curtain stretcher frame, wherein the frame member clamping means are permanently carried by the frame members, and wherein the openings for determining and adjusting the size of the curtain frame are in the top and side surfaces of the frame members instead of through the front faces as described in connection with the form of curtain stretcher illustrated in Figures 1 to 10 inclusive;

Figure 12 is a fragmentary front elevational view of the portion of the modified form of curtain stretcher form illustrated in Figure 11;

Figure 13 is an enlarged fragmentary front elevational view of the upper right-hand corner of the modified form of curtain stretcher frame with parts broken away showing the right end member moved inwardly from the right end of the upper frame member and held in place by an improved clamping arrangement which is permanently carried by the right end frame member for coaction with sizing holes mounted in the top surface of the top frame member; said figure also illustrates the position of the sizing holes in the right end member in substantially the same position as the holes through the right end frame member of the preferred form of curtain stretcher frame illustrated in Figure 1;

Figure 14 is a fragmentary top plan view of the portion of the modified form of curtain stretcher frame illustrated in Figure 13;

Figure 15 is a fragmentary transverse detail sectional view taken on line XV—XV of Figure 13;

Figure 16 is an enlarged fragmentary front elevational view of the lower right-hand corner of the modified form of curtain stretcher frame with the right end frame member moved inwardly from the end of the lower frame member, and also illustrating a clamping or securing bracket permanently carried by the right end frame member for coaction with receiving openings in the lower face of the bottom frame member;

Figure 17 is a fragmentary sectional view of the modified form of frame taken on line XVII—XVII of Figure 16; and

Figure 18 is a fragmentary transverse sectional view taken on line XVIII—XVIII of Figure 16.

As shown on the drawings:

The improved collapsible type of curtain stretcher of this invention is adapted to be quickly and easily set up by the average housewife or user and is designed to conveniently have the stretcher frame portion thereof quickly and accurately assembled, by positive sizing means permitting adjustment of the frame for stretching curtains of any desired size within the prescribed limits of the frame.

The improved curtain stretcher consists of only three units, which may either removably or permanently carry securing means for the quick and accurate assembly of the curtain stretcher. The three curtain stretcher units are of a type where-

in the members, constituting the same, may be easily collapsed to permit the unit to be assembled in compact form for storage or for placement in a storage or shipping container.

The curtain stretcher comprises a main or intermediate unit, a left end unit and a right end unit. The main or intermediate unit is of the self-supporting type and comprises a main supporting bar or standard 1 having a long longitudinally disposed slot 2 provided therein. Rigidly secured on the lower end of the standard 1, by means of bolts or other suitable fastening means, is a supporting foot 3, in the form of a plate, the ends of which project beyond opposite sides of the standard 1 to serve as a supporting base for the standard. Rigidly secured on the back of the upper portion of the standard 1 is a channel-shaped metal bracket 4 having engaged between the opposite flanges or blades thereof the upper chamfered end of an easel leg 5. The standard 1, together with the leg 5, form a self-supporting easel on which the upper and lower curtain stretcher frame members are permanently and adjustably engaged. When the self-supporting easel is opened the leg 5 is swung rearwardly into the inclined position shown in Figure 3 until the chamfered upper end of the leg engages flatly against the back surface of the upper portion of the standard 1 thereby making the intermediate unit of the curtain stretcher self-supporting.

The stretcher frame comprises a lower frame section, an upper frame section, a left end section and a right end section. The lower frame section is adjustably or slidably supported on the lower portion of the slotted standard 1 by means of a wing bolt 6 which projects through the slot 2 and through a lower frame hinge mechanism comprising a main hinge plate 7 of substantially triangular form having the lower portion thereof bent over to form a receiving channel 8. Pivotaly supported on the wing bolt 6 to the front side of the hinge plate 7 is an auxiliary hinge plate 9 the lower end of which is bent outwardly to provide a supporting flange 10.

The lower frame section or unit comprises two lower frame bars 11 and 12 constructed of wood or other suitable material each of which is cut out or milled to provide a stretcher pin carrying groove 13. The inner end of the lower frame bar 11 extends approximately half way into the receiving channel 8 of the hinge member 7 and is secured to said hinge plate 7 by means of bolts 14. The inner end of the lower frame bar 12 extends approximately half way into the receiving channel 8 of hinge member 7 and is secured to said hinge plate 9 by means of bolts 15. When the two lower frame bars 11 and 12 are in their lower positions, to form the bottom of the curtain stretcher frame, the inner end of the frame bar 12 projects into the hinge channel 8 and is aligned with the inner end of the frame bar 11 as clearly illustrated in Figure 1, and said bars by means of the channel 8 are adapted to be rigidly held in aligned position at a set of pre-determined selected height from the bottom of the standard 1 by sliding the bolt 6 into a desired position on said standard and then tightening the bolt 6 to hold the lower frame member in a selected position. Each of the lower frame bars 11 and 12 is provided with an angle-shaped bracket 16 to serve as receiving brackets for the reception of upper frame members, when the middle curtain stretcher unit is collapsed as hereinafter more fully described.

For the purpose of quickly and accurately

measuring the length of curtains which are to be stretched, each of the lower frame bars 11 and 12 is provided with a row of bolt receiving holes or openings 17 which are drilled through the thick portion of the frame bars and are spaced exactly one inch apart. The measuring or sizing holes 17, in the lower frame bars, are consecutively numbered from 1 to 92 starting at the left end of the lower frame section and continuing to the right. Engaged through the backs of the grooved portions of the lower frame bars 11 and 12, and having the pointed receiving ends thereof projecting into the grooves 13 of said bars, are a plurality of stretcher pins 18 one of which is positioned adjacent each of the sizing holes 17 as clearly illustrated in Figures 1 and 2.

The two lower curtain stretcher frame bars 11 and 12 are adapted to be pivotally swung upwardly into substantially parallel relation with the standard 1 to permit the upper ends thereof to seat in a channel bracket or pocket 19 secured to the standard 1 as shown in Figure 2.

From the foregoing description it will be noted that the lower frame section of the curtain stretcher is collapsible and is also adapted to be slidably adjusted upwardly from the lower end of the guide groove 2 toward the upper end thereof, when the clamping bolt 6 is released. This adjustable supporting of the lower frame unit is to permit curtains of different widths to be stretched.

Permanently but adjustably connected to the upper end of the easel standard 1 is an upper curtain frame section including a hinge unit comprising a main hinge plate 20 which is of substantially triangular form and has one margin thereof bent over to provide a receiving channel 21. The hinge plate 20 is pivotally supported on a pivot wing bolt 22 which is engaged through a hole provided in the upper end of the standard 1. Pivotally engaged on the bolt 22 is an auxiliary hinge plate 23 formed with a supporting flange 24. Secured to project into one-half of the hinge channel 21 is one end of a top curtain stretcher frame bar 25 which is held in the channel 21 by means of retaining bolts or rivets 26. Rigidly secured to the auxiliary hinge plate 23, by means of retaining bolts or rivets 27, is the inner end of a second top frame bar 28. Each of the upper frame bars 25 and 28 are also cut out or shaped in the form of a molding by cutting a groove 13 therein through which curtain stretcher pins 18 project. Each of the upper frame bars 25 and 28 are also provided with a row of sizing holes or openings 17, which are spaced exactly one inch apart, and said sizing holes are numbered starting from the left-hand end of the upper frame unit with the number 1 and continuing consecutively across the frame unit with the last hole being identified by the numeral 92. While the sizing holes of the upper and lower frame sections have been numbered from 1 to 92 for a maximum length of curtain of 92 inches, it will of course be understood that the upper and lower frame sections may be of any desired length with the sizing holes numbered accordingly.

By means of the upper hinge supporting mechanism for the two upper curtain stretcher frame bars 25 and 28, said bars may be collapsed or dropped downwardly to a position substantially parallel to the collapsed lower curtain frame bars 11 and 12, into the position illustrated in Figure 2, wherein the lower portions of the upper bars 25 and 28 are adapted to seat in the angle

brackets 16 of the lower bars thereby supporting both the lower frame bars and the upper frame bars in collapsed position on the intermediate easel, which is of the self-supporting type when the easel leg 5 is extended rearwardly as shown in Figure 3.

For the purposes of permitting the outer ends of the lower frame bar 11 and the upper frame bar 25 to be releasably connected to a left end section of the curtain stretcher, each of said frame bars has rigidly bolted to the back thereof a connecting plate 29 having an aperture therein for receiving a connecting bolt as hereinafter more fully described.

When the improved curtain stretcher is to be set up for use, the middle or main unit is set up first. This is done by merely moving the easel leg 5 into the open position illustrated in Figure 3 thereby permitting the middle standard 4 to be supported by the foot 3 and the leg 5 in a slightly inclined position. The top frame bars 25 and 28 which form the top longitudinal member of the frame are first swung from the full line positions of Figure 2 upwardly into the dotted line positions. When the upper frame bars 25 and 28 are moved into curtain stretching position the inner end of the top bar 28 is engaged in the channel 21 of the hinge unit thereby aligning the two top frame bars 25 and 28, as shown in full lines in Figure 1, to hold the top frame bars 25 and 28 in horizontal alignment. A wing bolt 30 is engaged through registering apertures in the hinge plates 20 and 23 and through a receiving opening in the upper portion of the main supporting standard 4. With the tightening of the locking bolt 30, the two upper frame bars are rigidly held in extended position ready for use.

After the upper frame bars are extended into curtain stretching position, the two hingedly connected lower frame bars 11 and 12 are pivotally swung downwardly from the full line positions illustrated in Figure 2 into the dotted line positions of said figure thereby permitting the inner end of the lower horizontal frame bar 12 to seat in the channel 8 of the hinge plate 7 to align the two lower frame bars in a horizontal position substantially parallel to the upper stretcher frame member. After the two lower frame forming bars 11 and 12 have been moved into their open curtain stretching position, the entire lower frame unit may be slidably adjusted upwardly on the main standard 4 by loosening the locking bolt 6 to permit the same to slide in the groove 2 until the lower frame member is in a selected position to define a predetermined width between the upper and lower frame sections of the curtain stretcher. After the lower frame section is set in a desired position, the locking bolt is tightened to hold the lower frame section clamped in place.

With the two upper and lower frame sections of the curtain stretcher moved into their open positions as described, the left-hand unit of the stretcher frame is adapted to be quickly and securely attached to the connecting plates 29 by means of a wing bolt or other suitable securing devices such as an upper clamping bolt 31 and a lower clamping bolt 32.

The left end unit of the curtain stretcher frame comprises a side frame bar 33 which is also formed with a curtain stretcher groove 13 through which side curtain stretcher pins 18 project forwardly into the groove. The side frame bar 33 is also provided with a plurality of spaced aligned sizing holes or openings 17 which are

spaced one inch apart and register with the side stretcher pins 18 in the side bar 33. The sizing holes 17 are consecutively numbered starting from the top and continuing downwardly reading from 1 to 54 which determines the maximum width of a curtain which can be stretched on the stretcher. If desired, the left end frame bar 33 may be made longer to accommodate more sizing openings to permit larger curtains to be stretched if necessary. The left end side frame member or bar 33 is of the same length as the main standard 4, including the foot 3, so that the lower end of the side bar or member 33 may serve as a supporting foot for the left-hand side of the frame.

Bolted or otherwise secured to the back of the side frame member 33 is a bracket 4 to which the upper end of an easel leg 5 is pivotally supported. The upper end of the leg 5, of the side member 33, is chamfered or beveled to permit the legs 5 on the backs of the main or intermediate standard 4 and the side frame member 33 to be extended rearwardly to brace the stretcher frame in position. By bolting the upper end of the side frame member 33 to the top connecting plate 29, the curtain frame bars 25 and 33 may be rigidly clamped together by means of the bolt 31 so that the pins in the side frame bar 33 are disposed in the same plane as the stretcher pins in both the upper and lower horizontal frame sections of the device and with a pin in exactly each corner of the frame. The connecting plate 29 of the lower frame bar 11 is adapted to be connected by means of the bolt 32 through any one of the sizing openings 17 in the bar 33 depending upon the horizontal positioning of the lower frame member for a selected width of curtain.

It will thus be noted that an improved curtain stretcher is provided in which the frame is so constructed that the upper and left-end members of the frame are adapted to be releasably bolted or secured together by simple fastening means and in which the lower horizontal member of the frame is adjustable on the standard 4 and on the side frame member 33 toward or away from the upper frame member to determine the width of curtains to be stretched.

One of the important features of the improved curtain stretcher is the construction of the right end frame unit which is illustrated in detail in Figures 4, 5 and 6. The right end frame unit is of the easel-type and comprises a right end member or bar 34 which is of the same length as the left-end bar or member 33 and is provided with a row of sizing holes or openings 17 spaced one inch apart and extending through said bar 34. The sizing holes in the right end bar 34 are numbered downwardly starting with 1 at the top with the last hole being numbered 54 to indicate the maximum width to which curtains can be stretched on the frame. If wider curtains are to be stretched, it will necessitate providing transverse frame members which are longer.

The right end frame bar or member 34 is adapted to be releasably secured to the right-hand end of the top frame bar 28 and the lower frame bar 12 by clamping bolts 35 and 36 respectively. The upper and lower end portions of the right-hand side bar 34 are engaged behind the upper and lower frame members and said bar 34 is adapted to be securely locked in place on the horizontal frame members to determine the length of the curtains to be stretched by inserting the upper and lower bolts 35 and 36 through the easily selected correctly numbered sizing

holes 17 of the upper and lower frame members. The position of the right-hand bar may be set in the extreme position illustrated in Figure 1 or in a position of adjustment nearer the left-hand bar 33 for stretching a curtain of less length according to the arrangement illustrated in Figure 4.

Adjustably mounted upon the right end frame bar 34 is a rotatably supported curtain stretcher unit comprising a rod or shaft 37 which is rotatably supported in bearing brackets 38, two of which are rigidly secured to the right end curtain frame bar 34 as clearly illustrated in Figure 6. A stop ring 39 is integrally or rigidly secured upon the upper portion of the control rod 37 and rests upon the upper supporting bracket 38 to hold the rod in position.

The upper end of the control rod 37 is bent over at right angles to form an operating handle 40. The control rod 37 is mounted adjacent the outer edge or side of the right end frame bar 34 and has pivotally supported thereon a plurality of curtain stretcher keys or blocks 41 which are separated from one another by means of thin friction washers 42. Each of the stretcher keys or blocks 41 is provided with a notch or groove 43. Engaged through each of the stretcher keys or blocks 41 from the back thereof is a curtain stretcher pin 18 which projects into the groove 43 of the key. The pins 18 engaged in the keys 41 as well as the pins 18 in the other frame members have the shank portions below the heads of the pins toothed or knurled so that after the stretcher pins are driven into position they will not work their way out of the keys or frame bars.

The stretcher pins 18 carried by the keys 41 are spaced one inch apart and are positioned to register with the holes or openings 17 in the right end frame bar 34. For the purpose of frictionally holding the curtain stretcher keys 41 in contact with one another so that all of the keys may be simultaneously swung by the rotation of the control rod 37, a coil supporting spring 44 is engaged around the lower portion of the rod 37 between the lower face of the lowermost key 41 and the lower bracket 38 as illustrated in Figure 6. Also engaged around the control rod 37 is an upper coil spring 45 which has the upper end thereof seated against the upper bracket 38 while the lower end of the spring 45 is seated against the top surface of the uppermost key 41. The springs 44 and 45 are so constructed that they work in opposite directions and hold the keys 41 and the separating washers 42 in frictional contact with one another so that all of the keys may be simultaneously swung from their open positions as illustrated in dotted lines in Figure 4 to closed curtain stretching positions as illustrated in full lines in said figure. When the keys are thrown into the full line positions illustrated in Figures 1 and 4 the row of curtain stretcher pins 18 carried by the keys are all positioned in alignment with one another and are all disposed in the same plane with the stretcher pins 18 in the other three members constituting the curtain stretcher frame. When the four frame members are connected, the pins are all in the same plane and with a pin located in exactly each corner of the set up frame. For the purpose of holding the control rod 37 in proper alignment against bending an intermediate bearing bracket 38 is secured to the right end frame bar 34. Said bracket is formed with an apertured plate through which the rod 37 projects.

For the purpose of supporting the right end

frame unit of the curtain stretcher, the right end curtain frame bar 34 has secured on the back thereof a channel-shaped bracket 4 in which the upper end of an easel leg 5 is pivotally supported as illustrated in Figure 5. It will thus be noted that when the frame is set up for use the three easel legs 5, which are pivotally attached to the frame members 1, 33 and 34, are swung rearwardly from said members into bracing positions. The entire stretcher frame is thus supported in an inclined position ready to have curtains accurately stretched thereon to a predetermined size depending upon the adjustment of the lower frame member and the right-hand end frame member with respect to the remaining two frame members. The full line positions of the lower and right-hand members illustrated in Figure 1 shows the stretcher frame set up for a maximum curtain stretching size. In the position of the adjustable frame members illustrated in dotted lines in Figure 1, the frame is set for stretching curtains of less width and less length than the maximum size for which the stretcher is designed.

Attention is called to Figure 4 of the drawings which shows a set up for the stretching of curtains of a determined width and length. To stretch a curtain of less width than the full width for which the curtain stretcher frame is designed, the clamping bolt 6 of the lower frame member 30 is released and the lower frame member is slidably moved upwardly from the full line position of Figure 1 into the dotted line position until the ends of the lower frame bars 11 and 12 register with the sizing openings 17 in the side bars 33 and 34 of the frame. At the time that the lower frame member is adjusted the control rod 37, of the right end frame unit, is swung to move the stretcher keys into the dotted line positions illustrated in Figure 4 so that the individually numbered sizing holes 17 in the bar 34 are exposed to permit the bolts 32 and 36 of the lower frame member to be inserted in the respective selected sizing holes 17 of the side bars 33 and 34. Such a positioning of the lower frame member will permit curtains to be stretched to the selected width and to the full length of the curtain frame. The upper and lower frame members are bolted to the bar 34 by means of the upper clamping bolt 35 and the lower clamping bolt 36 which are engaged through the last openings of said upper and lower frame members to set the curtain stretcher for a selected width less than the maximum width of the curtain stretcher adjustment and for the full stretching length of the frame.

After the curtain frame bar 34 is bolted in position as described, the handle 40 of the control rod 37 is rotated to simultaneously move all of the stretcher keys 41 from the dotted line open positions over into curtain stretching positions in contact with the front surface of the bar 34.

In case a curtain is to be stretched to a length less than the maximum length of the curtain stretcher frame, it is only necessary to swing all of the stretcher keys into their open retracted positions and then slide the right end curtain frame bar 34 into a predetermined adjusted position for the length of curtain desired which is easily determined by simply selecting the correctly numbered sizing holes in the top and bottom frame members. The upper and lower clamping bolts 35 and 36 respectively are then engaged through the selected sizing holes and are securely bolted in place by the wing nuts to set the frame for the required shortened length. The control rod 37 is now rotated to simultaneously

swing the stretcher keys to their stretching positions resting upon the front face of the bar 34 with the exception of two keys which are prevented from being rotated due to the adjusted positioning of the lower frame bar 12 which acts as a stop for the two keys as illustrated in Figure 10.

It will thus be noted that the improved curtain stretcher frame may be simply and quickly adjusted by means of the clamping bolts and the individually designated sizing holes 17, in the various frame members, so that no particular skill or degree of intelligence is required for perfectly setting up a frame for a definite size of curtain stretching. The sizing of the frame may thus be readily accomplished in a very short time with ease and celerity for stretching curtains to any desired width and length within the limits of the frame.

Referring now to Figures 11 to 18 inclusive, a modified form of curtain stretcher is illustrated which is substantially like the curtain stretcher illustrated in Figures 1 to 10 inclusive, with the exception that the upper, lower and left end frame members are of slightly different construction with respect to the location of the individually designated sizing holes. Another difference is in the provision of permanent clamping units for the corners of the adjustable curtain stretcher frame, which clamping units are adapted to be permanently carried by certain of the frame members instead of the removable clamping bolts such as used in the securing together of the frame members of the curtain stretcher illustrated in Figure 1.

In the modified form of curtain stretcher the parts which are the same as those illustrated in Figure 1 will be identified by the same reference numerals. In the modified form of frame the top frame member consists of two top frame bars 46 and 47 the adjacent ends of which are secured to hinge plates 20 and 23 respectively of the upper hinge unit carried on the upper portion of the intermediate or main standard 1. Each of the upper frame bars 46 and 47 is provided with a row of spaced sizing holes illustrated in Figures 11 and 14. The sizing openings 48 are spaced one inch apart with the first sizing opening on the left end of the member 46 arranged so that it will be spaced one inch from the upper stretcher pin 18 in the left end side frame bar 49 of the modified form of stretcher frame. The sizing openings 48 in the frame members 46 and 47 are numbered consecutively from 1 to 92 as a convenience for adjusting the frame for stretching a curtain to a predetermined or selected length.

The left end frame bar 49 is provided with sizing holes 50 in the outside face thereof. Rigidly secured to the back of the top left end frame member 46 is one end of an angle bracket 51 having a head 52 which is provided with an internally threaded opening through which a clamping bolt 53 is threaded. The inner end of the bolt 53 is provided with a stop ring 54 rigidly formed a short distance from the end of the screw bolt shank to leave a clamping stud 55 which is adapted to project into the uppermost hole 50 in the end bar 49 to hold the end bar rigidly clamped against the outer end of the top frame bar 46 when the clamping bolt 53 is threaded inwardly until the stop ring 54 tightly presses against the side surface of the side frame bar 49 as indicated in dotted lines in Figure 11. It will thus be seen that a device has been provided for securing the frame members 46 and 49 together by a clamping

device which is permanently carried by the frame member 46.

In the modified form of frame the lower frame member consists of two lower frame bars 56 which are respectively connected to hinge plates 7 and 9 similar to the arrangement illustrated in Figure 1. Each of the lower frame bars 56 is cut out to form a groove 13 into which the curtain stretcher pins 18 project. Each of the lower frame bars 56 is also provided with a plurality of sizing holes 57 in the bottom face thereof spaced one inch apart to register with the stretcher pins 18. The outer or left-hand end of the lower left frame bar 56 has rigidly secured on the back thereof an angle bracket 54 provided with a clamping bolt 53 similar to the arrangement for the upper frame member illustrated in Figures 11 and 12. A permanent clamping device for securing the lower end of the left end frame bar 49 to one end of the lower left-hand frame bar 56 is thus also provided and eliminates any danger of the frame clamping member from becoming detached and lost.

The changed form of curtain stretcher frame is completed by a right end frame unit comprising a right end frame bar 58 the front face of which is provided with a plurality of spaced aligned sizing holes 59 which are spaced one inch apart and are properly identified by a series of identification numbers placed conveniently on the front face of the left side frame bar 58. The identification numbers on the frame bar 58 start at the upper end and continue downwardly, said identification numbers ranging from 1 to 54 for a curtain stretcher frame designed for stretching curtains to a maximum width of 54 inches.

A control rod 37 and curtain stretcher keys or blocks 41 are furnished for the right end frame unit similar to the arrangement illustrated in Figure 1. The upper portion of the control rod 37 projects through apertures provided in a pair of spaced lugs or ears 60 forming an integral part of one flange of an upper clamping bracket which includes a channel-shaped body section 61 which engages around the back of the upper portion 45 of the side frame bar 58 and is rigidly secured thereto by means of screws or other suitable means. Integrally formed on one side of the channel-shaped body section 61 of the clamping bracket is an auxiliary or top frame bar clamping unit consisting of a plate or flange 62 disposed at right angles to one side of the channel body section 61 and projecting above the same. The upper portion of the plate 62 is bent outwardly at right angles to provide a top flange 63 having an internally threaded collar through which a clamping bolt 64 is threaded. Integrally formed on the lower portion of the threaded shank of the clamping bolt 64 is a stop ring 65 above a plain stud 66, which when the bolt is 60 threaded downwardly, is permitted to seat in one of the sizing holes 48 with the stop ring 65 tightly threaded against the upper face of the top surface of the top frame bar 47 to hold the bar 47 rigidly clamped to the upper portion of the right end frame bar 58. It will thus be noted that a frame clamping unit for releasably connecting the upper end of the right end frame bar 58 to the upper frame bar 47 is permanently carried on the end frame bar 58 to obviate misplacement or loss of the clamping means, which sometimes occurs when removable clamping bolts are used. The auxiliary clamping plate 62 has the lower end thereof bent outwardly to form a stop flange 67 against which the lower face 75 of the top stretcher frame bar 47 is adapted to

seat, as illustrated in Figure 15 when the frame members forming the upper right-hand corner of the curtain stretcher frame are clamped together.

For the purpose of clamping the lower portion of the right end frame bar 58 to the right end portion of the lower frame bar 56, a lower clamping unit is slidably engaged on the frame bar 58 and comprises two integrally connected substantially channel-shaped members disposed at substantially right angles to one another. One of the channel-shaped members is adapted to be engaged on the end frame bar 58 and comprises a bracket strip or plate 68 provided with an integral back flange 69 disposed at right angles to the plate 68. The bracket plate 68 is adapted to seat against the inner side of the frame bar 58 while the flange 69 seats against the back surface of said bar as illustrated in Figure 15. Integrally formed at right angles to the front end of the plate 68 is a front flange 70 which is formed with an internally threaded sleeve or collar 71 through which a clamping bolt 72 is threaded. A stop ring or circular flange 73 is integrally formed on the threaded shank of the bolt 72 to the inside of a plain tip or stud 74 which when the bolt 72 is threaded inwardly is adapted to engage in one of the holes 59 of the bar 58 to hold the corner clamping bracket secured in a predetermined set position on the right end frame bar 58. Integrally formed at right angles to one edge of the bracket plate 68 is a bracket section which is shaped to be slidably engaged on the lower right end frame bar 56 as shown in Figure 18. The lower frame bar bracket section comprises a back plate 75, a short top flange 76 formed at right angles thereto adapted to seat against the top edge of the bar 56. Integrally formed at right angles to the lower end of the back plate 75 is a bottom plate 77 having an opening therein to register with one of the bottom holes 57 of the bar 56. A front flange 78 is integrally formed on the front end and at right angles to the bottom plate 77 and seats against the front surface of the lower portion of the lower frame bar 56. Integrally formed at right angles to the second edge of the bracket plate 68 and opposite the bracket bottom plate 77 is a bolt supporting flange 79 having integrally formed thereon an internally threaded collar or sleeve 80 through which a clamping bolt 81 is adjustably threaded. The clamping bolt 81 is provided with an integral stop flange or ring 82 formed around the inner end of a plain tip or stud 83. The plain stud 83 of the clamping bolt 81 is positioned so that it can project through the opening in the bracket bottom plate 77 and projecting into a selected one of the sizing holes 57 provided in the bottom surface of the lower frame bar 56. It will thus be noted that the lower right-hand corner frame bracket may be slidably adjusted on the lower frame bar 56 and may also be adjusted vertically on the right end frame bar 58 to permit the modified form of curtain stretcher frame to be adjusted for stretching curtains of different lengths and widths.

In the modified form of curtain stretcher, illustrated and described, the main supporting standard as well as the side frame members 49 and 53 are each provided with a pivoted easel type leg 5 similar to the arrangement provided for the curtain stretcher illustrated in Figure 1.

It will thus be noted that an improved and simplified form of curtain stretcher has been provided wherein the upper and lower frame form-

ing members are pivotally or hingedly supported on the middle or intermediate standard of the curtain stretcher which is adapted to be self-supported by merely opening the easel leg attached to the back thereof. This arrangement permits the upper and lower frame forming members to be pivotally swung into curtain stretching position ready to have the end frame units attached thereto. Another important feature is the arrangement whereby the lower frame member and the right end frame unit may be adjusted with respect to one another and with respect to the top frame member to permit curtains of different sizes to be stretched on the curtain stretcher pins of the various frame members, all of said pins being disposed in the same plane with a pin located in each of the frame corners.

The novel arrangement of individually numbering or otherwise identifying each of the sizing holes in the four frame members permits the frame to be quickly and positively adjusted and assembled to a predetermined length and width by means of the corner clamping units for either forms of curtain stretcher described.

It is to be understood that various details and features of the construction may be varied through a wide range without departing from the principles of this invention, and it is, therefore, not the purpose to limit the patent granted hereon otherwise than necessitated by the scope of the appended claims.

I claim as my invention:

1. A collapsible type of curtain stretcher comprising end frame members, leg means engaged thereon for bracing the frame members in position to assist in supporting the curtain stretcher, a self-supporting intermediate supporting unit, upper and lower collapsible frame members pivotally supported on the intermediate unit, means for adjusting and then locking one of said collapsible frame members in extended position on the supporting unit, means for locking the other of said collapsible frame members in extended position on said intermediate supporting unit, clamping means connecting one of said end frame members to the extended upper and lower collapsible frame members, clamping means for clamping the other end frame member in adjusted position on the collapsible upper and lower frame members to form a curtain stretcher frame of a predetermined size, said collapsible upper and lower frame members and the left and right end frame members having openings therein for selectively receiving the clamping means for properly sizing the curtain frame, curtain stretcher pins carried by the left end frame member and the collapsible upper and lower frame members in registering relationship with the openings in said members and all disposed in the same plane when the frame members are assembled, a control rod rotatably supported on the right end frame member, and a plurality of spring controlled frictionally contacting pin carrying keys rotatably supported on the control rod and adapted to be simultaneously moved into an open position to permit the right end frame member to be secured to the collapsible upper and lower frame members, said pin carrying keys adapted to be simultaneously rotated to seat on the front face of the right end member to hold the pins on the keys in curtain stretching position in the same plane as the pins in the remaining frame forming members.
2. A collapsible type of curtain stretcher comprising upper, lower and end frame members

each having a row of equally spaced sizing openings therein, frame clamping means coacting with selected ones of said sizing openings to hold the frame members rigidly secured together to provide a curtain stretcher frame of a predetermined width and length, curtain stretcher pins on one of said end members and on the upper and lower frame members in spaced registered relationship with respect to one another and all disposed in the same plane when the frame members are secured together, a control rod on the second of said end frame members, a plurality of keys rotatably supported on said control rod, springs on said control rod for holding the keys in frictional movable contact with one another and normally permitting all of said keys to be simultaneously rotated with respect to said second end frame member, and stretcher pins carried by said keys and adapted to be moved into a position over said second end frame member by the rotation of the control rod to position the pins on said keys in registered relationship with the sizing openings in the second end frame member and in the same plane as the pins carried by the remaining frame members.

3. A curtain stretcher comprising a frame consisting of three frame members having stretcher pins permanently secured thereon and all disposed in the same plane, a fourth frame member connected to two of the three frame members, a rotatable support on said fourth frame member, a plurality of blocks pivotally supported on said rotatable support, means for securely holding the blocks in frictional contact with one another, and stretcher pins on said blocks adapted to be moved into and out of the plane of the pins of the other three frame members by the rotation of said rotatable supporting member.

4. In a collapsible type of curtain stretcher including an intermediate unit comprising a slotted supporting standard, means thereon to brace the same to stand independently, a lower hinge mechanism permanently and adjustably secured on the standard by a bolt extending through the slotted standard, means for locking the lower hinge mechanism in a set position on said standard, bottom frame members secured to the lower hinge mechanism and adapted to be extended into alignment with one another ready for use, said lower frame members also being adapted to be swung upwardly toward one another into substantially parallel relationship upon the supporting standard, bracket means on the supporting standard for receiving the lower frame members, an upper hinge mechanism mounted on the standard, upper frame members secured to the upper hinge mechanism and adapted to be extended into alignment with one another ready for use, means for locking the upper hinge mechanism in closed position to hold the upper frame members locked in alignment, said locking means adapted to be released to permit the upper frame members to drop downwardly toward one another into substantially parallel relation adjacent to the lower frame members, and bracket members on the lower frame members for receiving the upper frame members seated therein.

5. A curtain stretcher comprising a standard, means for making the same self-supporting, upper and lower frame forming members permanently connected to said standard, means for adjusting one of said frame forming members with respect to the other, an end frame member adapted to be removably secured to said upper and lower frame forming members, stretcher pins

on said upper and lower frame forming members and on said end frame member, said stretcher pins all adapted to be disposed in the same plane when said frame forming members are connected together, a second end frame member, means for connecting said second end frame member in different selected positions to said upper and lower frame forming members to provide a stretcher frame of a desired length, a plurality of pin carrying keys pivotally supported on the second end frame member, control means for simultaneously swinging said pin carrying keys into a retracted position while the second end frame member is being adjustably secured to the upper and lower frame forming members, said control means adapted to be operated to simultaneously swing the pin carrying keys from a retracted position into curtain stretching positions on the second end frame member with the exception of the pin carrying keys which contact the lower frame member when the same is moved into a position which interferes with the movement of certain of said pin carrying keys into stretching positions, said pin carrying keys when moved into stretching positions adapted to have the pins thereon positioned in the same plane as the pins in the remaining frame members to provide a stretcher frame wherein all of the pins are in the same plane and wherein there is always a pin positioned in each corner of the frame.

6. A curtain stretcher including a collapsible type of frame comprising an upper frame member and a lower frame member, a left end frame member, means for securing the left end frame member to the upper and lower frame members, stretcher pins on said frame members all disposed in the same plane and with a pin in each of the corners of the frame formed by said three members, and a right end frame unit comprising a frame bar, means for securing the frame bar to the upper and lower frame members at different selected positions thereon to provide a stretcher frame of variable length, a control rod rotatably supported on the frame bar, a handle for rotating said control rod, a plurality of blocks pivotally supported on the control rod, washers between said blocks, springs on said control rod for frictionally holding the blocks and washers in contact with one another, and a stretcher pin on each of said blocks, said control rod adapted to be operated by the handle for simultaneously moving all of the pin carrying blocks into retracted positions to permit the right end frame bar to be slidably adjusted on the upper and lower frame members and secured thereto, said control rod then adapted to be rotated by said handle to swing the pin carrying blocks into stretching positions seated on the frame bar to position the pins on said blocks in the plane of the pins on the remaining frame members and providing a pin in each of the corners formed by the intersection of the end frame bar with the upper and lower frame members.

7. In a collapsible type of curtain stretcher of the class described, a curtain stretcher frame forming unit comprising a frame bar, a control rod rotatably supported on one side thereof, a handle on said control rod, a plurality of blocks pivotally supported on said control rod, springs on said control rod for holding said blocks in frictional contact with one another to permit the blocks to be simultaneously rotated with the rotation of the control rod, and a stretcher pin on each of said blocks, said stretcher pins adapted

to be simultaneously moved into retracted positions by the rotation of the control rod in one direction and also adapted to be simultaneously moved into curtain stretching positions upon the frame bar with the rotation of the control rod in an opposite direction.

8. In a collapsible type of curtain stretcher a frame comprising three pin carrying frame members connected to form three sides of a stretcher frame with the pins on said members all disposed in the same plane, said pin carrying frame members having numbered sizing openings therein and a fourth frame unit comprising a frame bar having numbered sizing openings therein, clamping mechanisms for engaging selected sizing openings to clamp the end frame bar to two of the three frame members to form a stretcher frame of a predetermined size, spring controlled pin carrying stretcher blocks, and means for adjustably supporting the blocks on said frame bar and for moving the blocks to position the pins thereon in the plane of the pins of the remaining three frame members to provide a stretcher frame wherein all of the pins are disposed in the same plane and wherein the four corners of the frame each has a stretcher pin engaged therein.

9. A curtain stretcher comprising a frame constructed of four frame sections, pins rigidly secured on three of said frame sections and all disposed in the same plane, pin carrying supports rotatably carried by the fourth frame section, means for rotating said supports to position the pins thereon in the plane of the pins on the three frame sections, separators between said supports, and spring means for holding the separators and supports in frictional contact with one another to facilitate selective operation of the pin carrying supports.

10. A curtain stretcher comprising a frame constructed of four frame sections, three of which have stretcher pins rigidly secured thereon with all of said pins disposed in the same plane, the fourth frame section having stretcher pin carrying supports rotatably supported thereon in frictional contact with one another to permit the pin supports to be moved collectively or individually to position the pins thereon in the planes of the pins on the other three frame sections after the fourth frame section is secured in place, and springs on the fourth frame section for resiliently forcing the pin supports on said fourth frame section into frictional contact with one another from opposite directions to facilitate selective operation thereof.
